Primary Examiner — Jennifer L Watkins*Assistant Examiner* — Samantha Lynne Brodowski(74) Attorney, Agent, or Firm — Daniel M. Cohn;
Howard M. Cohn(57) **CLAIM**

The ornamental design for a shoe storage cabinet organizer, as shown and described.

DESCRIPTION

FIG. 1 is a perspective view of a shoe storage cabinet organizer showing my new design;

FIG. 2 is front view thereof;

FIG. 3 is a back view thereof;

FIG. 4 is a left view thereof;

FIG. 5 is a right view thereof;

FIG. 6 is a top plan view thereof;

FIG. 7 is a bottom plan view thereof; and,

FIG. 8 is an open state view thereof.

The broken lines showing a zipper depict portions of the article and form no part of the claim. All other broken lines in the figures depict stitching and form no part of the claim.

1 Claim, 8 Drawing Sheets(56)
